UNITED STATES PATENT OFFICE

HUGO F. SEMRAU, OF PITTSBURGH, PENNSYLVANIA

DESIGN FOR A COMBINATION PIPE STAND AND HOLDER FOR SMOKERS' ARTICLES

Application filed July 31, 1931. Serial No. 40,739. Term of patent 7 years.

To all whom it may concern:

Be it known that I, HUGO F. SEMRAU, a citizen of Germany, residing in Pittsburgh, Pa., in the county of Allegheny and State of Pennsylvania, have invented a new, original, and ornamental Design for a Combination Pipe Stand and Holder for Smokers' Articles, of which the following is a specification, reference being had to the accompanying drawings, forming a part thereof.

I claim:

The ornamental design for a combination pipe stand and holder for smokers' articles, as shown.

In testimony whereof I affix my signature.

HUGO F. SEMRAU.
